HOPPER CAR CONSTRUCTION

Karl F. Nystrom, Milwaukee, Wis.

Application April 16, 1938, Serial No. 202,492

10 Claims. (Cl. 105—247)

My invention relates to an improved hopper car construction wherein the hoppers are composed of a number of preformed elements and the hopper forming units suitably secured to the car side and at the center sill to provide a suitable center sill ridge, whereby an uninterrupted chute or hopper and moisture shedding structure is provided at both sides.

Another object of the invention is to provide an improved hopper construction that is more economical in construction and wherein the connections or junctures between the respective elements or units are such that they will compensate for variations in the hopper receiving openings formed in the previously constructed cars; the respective elements or units being formed to permit the units to be readily secured together into a unitary structure.

The invention also has for its object the provision of a construction wherein the relation between the hopper forming units and the car sills is such that air circulating passages between these units and the car sills are provided extending full length of the cars so that accumulation of moisture is prevented and the corrosive action heretofore encountered will be obviated.

The invention also contemplates a structure wherein the hopper side walls may be directly connected above the car sills and the side walls of the hoppers on opposite sides of the center sill connected together into a center sill ridge forming portion.

The enumerated objects and others, as well as advantages inherent in the invention, will be readily comprehended from the detailed description of the drawings, wherein—

Figure 1 is a plan view of the crown portion of the hopper car with my improvement.

Figure 2 is a sectional elevation as viewed along the line 2—2 of Figure 1.

Figure 3 is a perspective view of one of the crown sheet supporting and attaching castings or units.

Figure 4 is a transverse sectional view through the hopper portion of the car involving my invention.

Figure 5 is a perspective view of one of the brackets or elements employed at the car side wall adjacent the cross-ridge end of the hopper portion.

Figure 6 is a similar view of the other bracket or element employed at the car side wall adjacent the slope-sheet end of the hopper portion.

Figure 7 is a sectional elevation of the upper

part of the hopper side wall and a portion of the car side wall and embodying my invention.

Figure 8 is a sectional view taken on the line 8—8 of Figure 7, as viewed by the arrows.

Figure 9 is a transverse sectional view of the upper part of the hopper portion of the car illustrating a modification.

My invention contemplates the use of preformed elements preferably formed to eliminate the use of rivets and adapted more especially to be welded together during installation in the hopper openings of the car, with the adjacent surfaces formed to provide more or less elastic connections between the elements to compensate for certain variations in dimensions, thus enabling easier installation and the provision of a better construction.

As my invention relates to elements employed at the upper ends of the hopper portions of the car, the illustrations and description have been confined to the hopper portion of the car and particularly to the relation between the hopper side walls and the car sills and specific detailed description of the car proper and of the lower or dumping end of the bucket or hopper will not be entered into.

My improved structure is intended for use in a standard hopper car and especially to a structure wherein the hopper is composed of separately formed units and the hopper side walls comprising precast units adapted to resist corrosion and which lend themselves readily to welding operations. Referring to the drawings, the upper portions of the inner or center sill side walls of a hopper are shown at 20, 20, arranged on opposite sides of the center sill 21 shown in Figure 4. The upper end of the hopper inner side wall 20 is formed so it may be welded or otherwise secured adjacent the top of the center sill (see Figure 4) and also permit welding to the ridge cap members 22 or castings 22. I employ a pair of these members 22 at each end of the ridge; both members 22 being of similar construction, a detail view of same being shown in Figure 3. These members preferably consist of cast metal with the main portion which extends longitudinally of the center sill made with the oppositely sloping shedding walls 23, 23 and terminating at what may be called the outer ends in the wing portions 24, 24, united at top by the upwardly sloping flange 25, while the lower side of the casting is provided with the transversely disposed bridge forming rib 26, more clearly shown at the left in Figure 4, which seats on the center sill elements 21. The wings 24, 24 (which are disposed on opposite

sides of the center sill) slope upwardly and provide means for integrally connecting the slope sheets and transverse ridge forming sheets or members thereto, while the lower edges of the members 22 permit the inner side walls of the hoppers on opposite sides of the center sill to be integrally secured thereto. These members 22 also provide means of attachment for the ends of the crown sheet 27 as shown at 28 in Figure 1. 10 The crown sheet 27, like the members 22 is, of course, made with oppositely sloping walls to provide a proper shedding surface. With this construction the inner side walls of the hoppers on opposite sides of the center sill are intimately connected together and an uninterrupted junction provided against the accumulation of particles and moisture.

The outer side wall 29 of the hopper (which is also a precast unit) is usually secured to the 20 bottom leg or side of the angle beam or car side sill 30, as shown in Figure 4; this connection being generally made by riveting the hopper wall to the side sill as shown.

With this manner of formation as heretofore employed, the side sill provided an undesirable 25 ledge for the accumulation of material and moisture, and consequently early corrosion of the side sill and adjacent parts resulted.

My invention contemplates the provision of a 30 self cleaning and shedding structure consisting of a pair of bracket members or castings 31, 32, adapted to be employed at opposite ends of the bucket portion or hopper proper which provide suitable means of connection between the hopper outer side wall, the slope sheet and the car side 35 wall and also provide means for suitably supporting and attaching a shedding or filler plate; all of which are preferably integrally united with each other by welding.

40 The member 31 is intended to be used at the slope sheet side or end of the hopper and is formed with an outwardly sloping main wall 31^a terminating at top in a vertically disposed flange portion 33 which is adapted to extend substantially parallel with the car side wall 34; while the lower perimeter of the member is intended to be disposed at the inner longitudinal edge of the side sill 30.

The main body 31^a is cast with a number of 45 recessed portions as at 35, 36, 38; the recess 35 being formed to have a horizontal bottom adapted to rest on the inwardly disposed side of the side sill 30 as shown in Figure 4, and this horizontal bottom is provided with a hole 37 to permit the member 31 to be secured to the horizontal inwardly disposed side of the car side sill 30, as for example by a plug weld as at 38 in Figure 4.

The recesses 35, 36 in member 31 are formed with vertically disposed walls having holes, as at 50 39; the vertical wall portions of the recesses being intended to extend flush with the upstanding side of the side sill 30 as shown to the right in Figure 4, and the holes 39 being provided to enable the member or casting 31 to be plug welded to the side sill as shown at 40 in Figure 4.

The casting 31, at a suitable point, as for example intermediate of the recesses 35, 36, is shown 55 formed with the vertically disposed rib 41 which curves inwardly and terminates in the horizontally extending ledge or stake supporting and attaching arm 42 on which the adjacent car side wall stake 43 rests and may be secured. The upper flange portion 33 of the member or casting 31 rests against the car side wall 34 and is preferably welded to the car wall full length of the

flange as shown at 45 in Figure 8; while the bottom of the car side wall is also welded to the side sill 30 as indicated at 46 in Figure 8, thus providing an integral connection between the car side wall, casting and side sill, as well as an integral connection between the casting and the side sill. 5

The tapered end of the casting 31 is shown provided with off-set portions or flanges 47, 48, to afford means for providing lapping connections 10 with the slope sheet and with the hopper bottom; the flanges 47, 48 being formed to accommodate themselves to the usual formation of the elements mentioned and provide support for those elements and to permit the latter to be welded 15 to the casting 31.

The opposite end of casting 31 is provided with an offset flange 51 for the purpose of receiving one end of a filler sheet or plate 52 which is intended to be welded to casting 31; the flange 51 being arranged with the same inclination or slope as the casting 31. 20

At the cross ridge end of the hopper I employ member or casting 32, whose main wall 32^a also slopes outwardly toward the top where it terminates in the vertically disposed flange 53 which is to be arranged flush with the car side wall 34 and to be welded thereto throughout the top of the casting, similar to that of casting 31 and as shown at 45 in Figure 8. 30

This member or casting 32 at one end has an off-set upwardly sloping flange 54 to receive and support the adjacent end of the filler sheet or plate 52 as shown in Figure 7. This same end of the member or casting is cast with the vertical 35 rib 55 which terminates at top in the horizontally extending arm 56 for supporting the adjacent side wall stake, which may be welded thereto.

The main portion 32^a of the casting adjacent the top and bottom is provided with recesses 57, 58; 40 the inner wall of recess 57 being vertically disposed to extend flush with the vertical side of the car side sill 30; and this wall is provided with a hole to receive fastening means, such as a plug weld 40 for intimately securing it to the side sill. 45 The recess 58 is formed with a bottom horizontal wall provided with a hole to permit the casting 32 to be plug welded to the side sill as shown at 38 in Figure 4; in a manner similar to casting 31.

The other or tapering end of casting 32 is shown 50 formed with the inwardly extending flanges or portions 59, 60 and 61.

The flange portion 59 is intended to receive the adjacent edge of the hinge butt plate, a portion whereof is shown at 64 in Figure 7, and permits 55 the latter to be welded to the casting 32. The flange portion 60 is preferably offset upwardly and is provided with the offset flange portion 61 intended to receive the end of the cross ridge sheet 50 of the car; the sheet abutting against 60 the flange portion 60, to which it may be welded.

As the flanges 51 and 54 of members or castings 31 and 32 are arranged at an inclination, the filler plate 52 will likewise be held at an inclination, with the lower edge of the plate arranged adjacent the outer side wall 29 of the hopper and this edge of the plate is preferably welded to the hopper side wall; while the upper longitudinal edge of the plate is welded to the car side wall so as to provide an intimate shedding relation between the plate and side wall; the plate 52 intermediate of its ends being bent or provided with the offset portion 66 to receive the side wall stake 43 (see Figure 7) to permit the latter to be welded thereto. 70

With this construction a greatly reenforced and integrally connected structure is produced with shedding surfaces; a structure which also lends itself to variations in the hopper receiving opening in the car as a result of the lapping connections between the respective elements.

In Figure 9 I disclose a modification wherein the hopper side wall members or units 67 and 68 are of greater vertical dimensions in order that they may overlap or extend above the respective sill members.

The hopper outer wall 67, where it contacts the lower side of the side sill 30, is made to slope outwardly at 69 toward the car side wall 34 and terminates in a vertically disposed flange portion 70 above the side sill and this flange portion is welded to the car side wall. The sloping portion 69 overlaps and covers the side sill and provides a shedding surface and at the same time produces an air circulating space between the hopper side wall and the side sill, similar to that produced by the castings 31, 32 and the filler plate 52.

The inner side wall 68 of the hopper adjacent the lower flange of the center sill member 21 slopes upwardly at 71 and thence in an inclining manner across the top of the center sill and terminates in a vertical flange portion 72, which is disposed substantially at the longitudinal median line of the center sill, where it is arranged in side to side relation with the flange portion 72 of the hopper side wall member 68 of the hopper on the opposite side of the center sill; the flange portions 72 of both hopper walls being welded together and forming a very rigid crown portion over the top of the center sill which will permit complete outflow or dumping and which will not permit accumulation of moisture.

The respective elements are preferably of cast metal or cast steel because it is not as readily affected by moisture and corrosive action as is the case with rolled steel; and my invention provides hopper portions composed of separate elements affording considerable elasticity in the adaptation to a car and which are all intimately united into an integral unit.

The exemplifications of the invention are believed to be the best embodiments which have been described in terms employed for the purpose of description and not as terms of limitation as structural modifications are possible and may be made without, however, departing from the spirit of the invention as defined in the appended claims.

55 What I claim is:

1. A hopper car construction comprising a plurality of preformed members adapted to constitute the side walls of the hopper portion, anchoring members and fill sheets, certain of the anchoring members being adapted to slope upwardly from the base of the car side sill to the top thereof, with the upper ends secured to the car side wall while the lower end is secured to the base of the side sill, said members being provided with a side stake supporting and attaching portion; other members arranged in straddling relation with the car center sill and secured to the adjacent side walls of the hoppers on opposite sides of the center sill; a fill sheet disposed between the members on the car side sill and sloping toward the car side wall and united therewith, the ends of said fill sheet being integrally united to said first mentioned members; and a crown sheet disposed across the center sill mem-

bers, the ends of said crown sheet integrally secured to the last mentioned members.

2. A hopper car construction comprising cast metal units constituting hopper portion side walls, anchoring and bridging members, and fill plates; certain of said members bridging the angle of the car side sills and disposed thereabove in longitudinal spaced relation and integrally secured to the car side walls and to the car stakes, while the other members bridge the tops of the car center sill and are longitudinally spaced apart; the fill plates being arranged between the respectively spaced members and their ends secured thereto; the members being, respectively, intimately secured to the side sills and to the center sill and to the adjacent hopper side wall units by welding.

3. In a hopper car construction, anchoring members arranged at opposite sides and ends of the hopper portion of the car so as to slopingly overlap the car side sills and the car center sill; and fill plates intermediate of the respective anchoring members with their ends integrally connected thereto and adapted to provide shedding surfaces with air circulating passages between the side sills, the center sill and the fill plates.

4. A hopper car construction comprising cast metal elements, certain of the elements being integrally united with the car side sill and car side wall to provide a shedding surface across the side sill with an air space therebeneath, while the other members are united across the top of the car center sill into a shedding ridge with an air space therebeneath.

5. A hopper car construction comprising, in combination with the side walls of the hopper, precast anchoring members formed with sloping faces, one pair of said members being disposed at each end of the hopper portion and adapted to bridge the inner angle of the car side sill and be secured thereto, while the other pair of said members are disposed at each end of the hopper portion in bridging relation with the car center sill, all of said members being formed with attaching flanges to provide lapping joints with adjacent elements of the car; a slope plate disposed between the first mentioned pair and intimately secured thereto and to the car side wall; and a crown plate disposed across the center sill between the second mentioned pair of members, with its ends intimately secured to said members; the first mentioned pair of members having side wall stake supporting and attaching ledges.

6. In a hopper car construction, preformed anchoring members having upwardly sloping faces and adapted to be secured on the inner angle of the car side sill, each of said members tapering upwardly at one of the ends and provided with flange portions adapted to effect lapping connection with the slope sheet and hopper bottom and with the hinge-butt rail and ridge sheet; each of said members being provided with recesses having apertured surfaces adapted to contact the vertically and horizontally disposed sides of the car side sill to permit said members to be welded to the side sill; while the top perimeters of said members are disposed vertically to extend flush with the car side wall and be secured thereto.

7. In a hopper car construction, pre-cast anchoring members for the adjacent elements of the car, certain of the members being adapted for anchoring the outer side walls of the hopper portion of the car, while the other members are adapted for anchoring the inner side walls of the

- hopper portion of the car; the first mentioned members being made with sloping faces provided with inset surfaces to contact the vertical and horizontal sides of the car side sill angle, said surfaces being formed with plug weld receiving holes whereby said members may be integrally united to the side sill in sloping relation therewith, the upper longitudinal perimeters of said members being vertically disposed and arranged parallel with the car side wall and intimately secured thereto; the second mentioned members being formed with oppositely sloping surfaces and a transverse rib extending from side to side adapted to rest on and to bridge the car center sill with the marginal edges of the inner side walls of the hoppers on opposite sides of the center sill secured thereto and having extensions for securing the slope and ridge sheets of the car thereto.
8. In a hopper car construction, pre-cast single piece members formed with sloping surfaces adapted to extend from the hopper outer wall to the car side walls, terminating at top in vertically disposed portions for lapping the car side walls and to be secured thereto, said members being formed with rearwardly disposed apertured recessed portions adapted to contact the horizontal and vertical sides of the car side sills and to be integrally united therewith, said members being provided with side stake supporting and attaching extensions.
9. In a hopper car construction, a pair of pre-cast single piece members arranged in longitudinal spaced relation and formed with sloping surfaces adapted to extend from the hopper outer walls to the car side walls, the tops of said

members being provided with vertically disposed portions for lapping the car side walls and to be secured thereto, said members being formed with rearwardly disposed recessed portions adapted to contact the horizontal and vertical sides of the car side sills and to be secured thereto, the members being provided with side stake supporting and attaching extensions and having offset flanges at one of their ends; and a sloping fill sheet arranged between said spaced members with its ends intimately secured to said offset flanges.

10. In a hopper car construction, a precast single piece ridge cap member, adapted to be disposed on the center sills of the car, tapering toward one end and having downwardly and outwardly sloping uninterrupted top surfaces on opposite sides of the longitudinal median line, each sloping surface at its lower marginal edge having a vertically disposed portion adapted to be integrally connected with the inner side wall of the hopper on the adjacent side of the car center sill, the sloping surfaces of the member adjacent the tapered end having laterally disposed and upwardly sloping wings for attaching the car slope sheets thereto, while the sloping surfaces at the other end of the member are provided with a downwardly offset marginal portion to permit overlapping attachment of a crown sheet thereto; the lower sides of the sloping surfaces being connected by a transverse rib formed to support the member on the car center sill and to permit air circulation between the member and the center sills.

KARL F. NYSTROM. 35
